UNITED STATES PATENT OFFICE.

JAMES THOS. WHITE, OF ANACONDA, MONTANA, ASSIGNOR OF ONE-HALF
TO CHARLES S. PALMER, OF ANACONDA, MONTANA.

SPOUT FOR BLAST-FURNACES.

SPECIFICATION forming part of Letters Patent No. 782,298, dated February 14, 1905.

Application filed May 24, 1904. Serial No. 209,498.

To all whom it may concern:

Be it known that I, JAMES THOS. WHITE, a citizen of the United States, residing at Anaconda, in the county of Deerlodge and State of Montana, have invented a new and useful Spout for Blast-Furnaces, of which the following is a specification.

This invention relates to spouts for blast-furnaces.

10 The object of the invention is in a ready, practical, and thoroughly feasible manner to reduce the cost of production of such spouts, to facilitate and cheapen repairs, measurably to increase the life of the spout, and generally to improve devices of the character named.

With the above and other objects in view, as will appear as the nature of the invention is better understood, the same consists in the 20 novel construction and combination of parts of a spout for blast-furnaces, as will be hereinafter fully described and claimed.

In the accompanying drawings, forming a part of this specification, and in which like characters of reference indicate corresponding parts, there are illustrated two forms of embodiment of the invention, each capable of carrying the same into practical operation, it being understood that the elements therein exhibited may be varied or changed as to shape, proportion, and exact manner of assemblage without departing from the spirit thereof.

In the drawings, Figure 1 is a view in perspective of a furnace-spout constructed in accordance with the present invention. Fig. 2 is a longitudinal sectional view thereof.

Referring to the drawings and to Figs. 1 and 2 thereof, 1 designates the shell of the spout; 2, the heads; 3, the tie-rods for holding the 40 heads assembled with the shell, and 4 the nuts for securing the tie-rods in position. The shell may be made of any suitable material, preferably of boiler iron or steel, and the heads or plates 2 may be made of cast-iron, cast-steel, or drop-forged steel.

In carrying the invention into effect a sheet of steel or iron of the proper size is taken and formed by suitable mechanism into the frustum of a cone, and then the edges are joined

by welding or riveting. This cone frustum 50 is then flattened and bent into a double-walled half-cone frustum, the ends of which are trued in any suitable manner. The heads 2 are then assembled with the shell thus formed and are held in position thereon through the medium 55 of the tie-rods 3, which extend throughout the entire length of the spout, the nuts 4 and the heads 5 of the tie-rods being countersunk to lie within the outer plane of the heads, thus to obviate the presentation of obstructions and, further, to secure a water-tight juncture between the parts. In order that there shall be no leakage between the heads and the shell, the ends of the latter are beveled or pointed at 6, these beveled portions 60 being engaged by similarly-shaped grooves 7, formed on the inner faces of the heads, as clearly shown in Fig. 2. Of course it is to be understood that a suitable lute may be included between the heads and the shell, and 70 as this is a well-known expedient illustration is deemed unnecessary. The shell is provided at one end with an opening 8 to receive a water-pipe, as usual. The opposite end is provided with a series of openings 9, two of which 75 will always remain sealed, while the third will be engaged by a water-pipe, thus giving circulation through the spout. As the outer or small end of the spout is that which is subjected to the greatest heat, and thus burns out, it 80 is necessary that the series of openings 9 should be provided, so that when the end is cut off for purposes of making a new joint there will be a hole ready to receive the water-pipe. The holes not in use may be sealed 85 by ordinary screw-threaded plugs. Two or more extra heads will be furnished with each spout, and where the outer end is burned off it will be cut off at the line A or B, as the case may be, and a new head somewhat larger 90 than the original substituted for the one removed, it being seen that the cone-shaped contour of the spout will render this necessary.

A great feature of advantage in this form of spout over those in ordinary use is that 95 where the outer or front end of the spout is burned off the spout may be trued and a new head applied without the necessity of employ-

ment of skilled labor for the purpose, and, further, there will be but slight loss of time in effecting repairs.

While the shell is herein described as being provided with beveled ends, it is to be understood that the invention is not to be limited to this arrangement, as the ends may be square. Furthermore, the heads of the spout may be arranged in parallelism, or the rear head may be disposed at an incline to the front head, or vice versa, as may be found necessary or desirable.

Having thus described the invention, what is claimed is—

A furnace-spout comprising a hollow shell 15 provided in its outer side near one end with a plurality of water-inlet supply-openings arranged in alinement and longitudinally of the spout, and near the other end with a water-outlet opening, and heads detachably connected 20 with the shell.

In testimony that I claim the foregoing as my own I have hereto affixed my signature in the presence of two witnesses.

JAMES THOS. WHITE.
